UNITED STATES PATENT OFFICE.

HENRY A. CARPENTER, OF SEWICKLEY, PENNSYLVANIA, ASSIGNOR TO RITER-CONLEY MANUFACTURING COMPANY, OF PITTSBURGH, PENNSYLVANIA, A CORPORATION OF NEW JERSEY.

COAL-GAS-GENERATING APPARATUS.

1,140,793.

Specification of Letters Patent.

Patented May 25, 1915.

Application filed January 2, 1915. Serial No. 118.

To all whom it may concern:

Be it known that I, HENRY A. CARPENTER, a citizen of the United States, residing at Sewickley, in the county of Allegheny and State of Pennsylvania, have invented certain new and useful Improvements in Coal-Gas-Generating Apparatus, of which the following is a specification.

The primary object of this invention is to provide improved and efficient means for maintaining communication between the retort and stand-pipe of gas generating apparatus, the invention including means for admitting liquid to the communicating passage for cooling the gas as it flows from the retort, thereby minimizing the accumulation in the passage of stoppage-forming deposits.

In the preferred adaptation, the invention is embodied in a connecting conduit which has a controlling valve located at its retort end and with a liquid spray device within the conduit, the latter being preferably inclined in order to drain into the stand-pipe.

The invention also includes a retort-mouth-piece of novel construction having a lateral offset provided with a seat-forming surface for the valve and with the gas conduit extending from said surface to the stand-pipe.

In the accompanying drawings, Figure 1 is an elevation of a portion of a bench or benches of gas retorts embodying the invention. Fig. 2 is a sectional elevation of one of the stand-pipes and the retort mouth-pieces in communication therewith, taken on line 2-2 of Fig. 3. Fig. 3 is a sectional plan taken on line 3-3 of Fig. 2. Fig. 4 is a sectional elevation of one of the mouth-pieces taken on line 4-4 of Fig. 3.

Referring to the drawings, 2 designates a gas bench, and 3 are the retorts, as here shown the latter being arranged one above the other in vertical rows. Two rows of retorts may be disposed relatively close to each other and served by the single stand-pipe or offtake 4, or a separate stand-pipe may be provided for each row, all as shown in Fig. 1.

Each retort is in separate communication with the stand-pipe through the lateral conduit 5 which is preferably inclined as shown, its length depending upon the space intervening between the retort and stand-pipe.

In the specific embodiment here shown, the retort mouth-piece 6, having its open front end closed by door 7, is formed in-

wardly from said end with the lateral offset or enlargement 8, the general form of which is triangular, and with conduit 5 opening outwardly and downwardly from the seat-forming face or wall 9 of the offset. The conduit preferably opens through the lower portion of face 9 so that the valve 10 which operates on said face is in lowered position when closing the conduit. The valve is adapted to move to the upper portion of face 9 when open, as shown in dotted lines in Fig. 4, leaving the conduit in unobstructed communication with the mouth-piece.

As here embodied, the valve is of disk form and is pivoted at 11 to the valve-operating arm 12, the latter secured to one end of shaft 13. The shaft extends through a housing 14 which may comprise an integral part of the mouth-piece, the shaft projecting therethrough and provided with the external operating arm 15. A spring 16 within the housing holds the shaft under constant tension with the valve pressed toward seat 9. With the valve pivoted at 11, its position may shift and thus cause it to wear uniformly as it slides on face 9 and always insure a gas-tight fit over the extremity of conduit 5.

To minimize the accumulation of stoppage deposit within conduit 5, a pipe 17 is entered therein from which cooling liquid may discharge in the form of a spray. The pipe is preferably located close to the valve-closed end of the conduit and discharges toward the stand-pipe so that substantially the entire length of the latter is subjected to the cooling action of the liquid. With the conduit inclined as shown, the cooling liquid and the solids carried thereby will drain into the stand-pipe. The cooling liquid may be supplied from any suitable source.

With the cooling liquid constantly introduced into the passageway, the temperature of the gas is reduced immediately upon leaving the retort, and the resulting relatively low temperature at which the passageway is maintained greatly reduces the stoppage tendency, and correspondingly eliminates much of the cost and inconvenience incident to frequent cleaning.

While the valve and the liquid spray are designed for conjoint use, either may be used independently of the other without departing from the invention. As to the valve,

this will be readily understood when it is remembered that in some forms of apparatus valves are not employed in the passageways connecting the retort and stand-pipe.

5 5. What I claim is:—

1. In gas generating apparatus, the combination of a retort, a stand-pipe, a gas conduit connecting the retort and stand-pipe, a 10 valve for the conduit spaced from the point of communication between the latter and the stand-pipe, and means for discharging a cooling medium into the conduit intermediate the valve and stand-pipe.

15 2. In gas generating apparatus, the combination of a retort, a stand-pipe, a gas conduit connecting the retort and stand-pipe and constantly open to the latter, a valve for the conduit located at the rear end thereof, 20 and means for spraying liquid into the conduit intermediate the valve and stand-pipe.

25 3. In gas generating apparatus, the combination of a retort, a stand-pipe, a gas conduit at one end in communication with the retort and inclined downwardly therefrom and at its opposite end in communication with the stand-pipe, a valve for the conduit spaced from the stand-pipe end of the latter, and means for discharging a cooling 30 medium into the conduit intermediate the valve and stand-pipe.

35 4. In gas generating apparatus, the combination of a retort having a door-closed opening, a stand-pipe, a gas conduit in communication with the stand-pipe and with the retort adjacent to its door-closed opening, a valve for the conduit spaced from the stand-pipe, and means for discharging a cooling medium into the conduit intermediate the valve and stand-pipe.

40 5. In gas generating apparatus, the combination of a stand-pipe, a retort and a retort mouth-piece, the latter having a door-closed opening and an offset located inwardly from said opening and in communication with the stand-pipe, a valve for the conduit spaced from the stand-pipe, and means for admitting fluid to the conduit between the valve and stand-pipe.

45 6. In gas generating apparatus, the combination of a retort, a stand-pipe, a gas conduit in communication with the stand-pipe and with the retort, and means for admitting a cooling medium into the conduit.

50 7. In gas generating apparatus, the combination of a retort, a stand-pipe, a gas conduit in communication with the retort and stand-pipe and downwardly inclined toward the latter, and means for admitting a cooling 55 medium into the conduit which drains

into the stand-pipe by reason of the inclination of the conduit.

8. In gas generating apparatus, the combination of a retort and a retort mouth-piece, the mouth-piece having a door-closed 65 end and a lateral seat-forming offset adjacent said end, a gas conduit open at one end through the seat-forming surface of the offset and at its opposite end open to the stand-pipe, a valve slidable over the seat-forming 70 surface and adapted to open and close the conduit, and valve-actuating means.

9. In gas generating apparatus, the combination of a retort and a retort mouth-piece, the mouth-piece having a door-closed 75 end and a lateral offset formed with an inclined seat-forming face, a gas conduit opening through said face and inclined downwardly toward and in communication with the stand-pipe, a valve slidable over 80 said inclined seat-forming face and adapted to open and close the conduit, and valve-actuating means.

10. In gas generating apparatus, the combination of a plurality of retorts, a stand-pipe, a laterally extending gas conduit for each retort and at one end open thereto, the opposite ends of the conduits open to the stand-pipe, a valve for each conduit spaced from the stand-pipe, and means for admitting 90 a cooling medium to the conduit intermediate the valve and stand-pipe.

11. In gas generating apparatus, the combination of a plurality of gas retorts, a mouth-piece for each retort forming an end 95 continuation thereof, each mouth-piece having a door-closed opening and a conduit forming offset located adjacent said opening, a stand-pipe, said conduit-forming offsets extending to and in communication 100 with the stand-pipe, a valve for each conduit-forming offset spaced from the stand-pipe, and means for admitting a cooling medium to the offset intermediate the valve and stand-pipe.

12. In gas generating apparatus, the combination of a retort, a stand-pipe, a conduit extending laterally from the retort and at one end open thereto and at its opposite end open to the stand-pipe, and a valve at the 110 retort end of the conduit with the entire length of the latter constantly open to the stand-pipe.

In testimony whereof I affix my signature in presence of two witnesses.

HENRY A. CARPENTER.
